UNITED STATES PATENT OFFICE

ARTHUR ROBERTS, OF EVANSTON, ILLINOIS, ASSIGNOR TO AMERICAN COKE & CHEMICAL COMPANY, OF CHICAGO, ILLINOIS, A CORPORATION OF MAINE.

COKE-OVEN HEATING-WALL AND THE LIKE.

1,353,781.

Specification of Letters Patent. Patented Nov. 16, 1910.

Application filed January 27, 1910. Serial No. 273,281.

To all whom it may concern:

Be it known that I, ARTHUR ROBERTS, a citizen of the United States, residing at Evanston, in the county of Cook and State of Illinois, have invented certain new and useful Improvements in Coke-Oven Heating-Walls and the like, of which the following is a specification.

The present invention has to do with certain improvements in coke oven heating walls and the like, but it will presently appear that the features of the invention are in no wise limited to use in connection with coke oven heating walls, inasmuch as they may be used with equal advantage in many cases in the construction of other coke oven walls.

In my co-pending application for Letters Patent of the United States on improvements in coal distillation retorts, Serial No. 120,351, which was filed September 15, 1910, I have disclosed a form of coke oven in which the heating walls are built up from horizontal courses of blocks, which blocks are so formed that there is provided a mesh-work of interconnected gas passages on the interior of the wall. These blocks are so constructed that, as the gases flow in a generally horizontal direction from one side of the wall to the other—in other words, in a direction generally parallel to the direction of the courses of blocks—the gases are deflected or thrown back and forth and caused to impinge with violence against portions of the wall.

The present invention has to do with an improved type of coke oven wall in which the meshwork of impingement passages is so formed that, as the gases travel in a direction generally parallel to the direction of the courses, the gases will be thrown or impinged back and forth against different portions of the wall. Furthermore, the present invention has to do with a construction of notched blocks which are so formed that, when set together, they will provide the aforementioned heating wall having gas passages of the character mentioned.

Other objects and uses of the invention will appear from a detailed description of the same which consists in the features of construction and combinations of parts hereinafter described and claimed.

Referring to the drawings:

Figure 1 shows a fragmentary vertical section through a portion of the interior of the wall, being taken on the line 1—1 of Fig. 2, looking in the direction of the arrows;

Fig. 2 shows a horizontal section taken on the line 2—2 of Fig. 1, looking in the direction of the arrows;

Figs. 3 and 4 respectively show a horizontal plan and a vertical elevation of one of the notched blocks used in the construction of the wall shown in Figs. 1 and 2; and

Figs. 5 and 6 show respectively a horizontal plan and a vertical elevation of one of the key-stone blocks which is used in the construction of the said wall.

The heating wall herein disclosed comprises a series of courses, each formed or built up from notched blocks of the detailed construction shown in Figs. 3, 4, 5, and 6. Each block is shown as being recessed on its faces at the points 7 and 8, the recess 7 lying in the direction of the course, and the recess 8 lying across the course. The central portion of the block 9 lies adjacent to one side of the block, so that the central portion 9 is thus off-centered. Furthermore, this central portion 9 lies adjacent to one of the horizontal faces of the block, the recess 7 being adjacent to the other horizontal face. Consequently, when each block is set into place in its course, the central or web portion 9 will occupy a position adjacent to one corner of the block, as is well shown in Fig. 1.

It is to be observed that the central portion 9 of each block is of semi-hexagonal cross section presenting the faces 10, 11, and 12. Consequently, when two of these blocks are set together with their flat faces 13 in contact, a hexagonal cross bar or baffle member will be provided.

In building up a wall from these blocks, the following procedure may be adopted: One block will be laid with its central portion 9 in the lower right hand corner; the next block of that course will be laid with its central portion 9 in the upper right hand corner, this being done by turning the block end for end and also turning its other face upward; the next block will be laid in the same position as the first one; the next block in the same position as the second one.

et seq. In laying the next course, a similar procedure will be adopted, but the blocks will all be turned end for end as compared to the corresponding blocks of the course 5 below, so that the central portions 9 of the blocks of the two courses will be brought into proper coöperative relationship.

Owing to the presence of the notches 8 in the blocks, vertical passages 14 will be 10 established in the completed wall. Horizontal passages 15 will be established between the blocks of the pairs of courses, by reason of the presence of the notches 7. However, on account of the alternate reversal 15 of the positions of the consecutive blocks in each course, the passages 15 step alternately up and down, as the path is followed across the wall, so that gases flowing in a generally horizontal direction are baffled 20 and caused to impinge with violence against portions of the blocks. When the notches 7 are relatively shallow enough as compared to the thickness of the central portions 9, the passages 15 will be completely baffled, so 25 that it will be impossible for any portion of the gas to travel horizontally without encountering a baffling surface.

While I have herein shown and described only a single embodiment of the features of 30 my invention, still it will be understood that I do not limit myself to the said embodiment, except as I may limit myself in the claims.

I claim:

35 1. A coke oven heating wall comprising courses of blocks, each block having two conjoint recesses in two of its adjoining faces, and having a connecting section in the corner away from said recesses, said connecting section having its two edges beveled, the blocks of each course being laid with their connecting sections all facing in the same direction along the length of the wall but with their connecting sections alternately at the top and at the bottom of the course, and the connecting sections of successive courses 40 facing alternately toward the opposite ends of the wall, substantially as described.

cessive courses facing alternately toward the opposite ends of the wall, substantially as described.

2. A coke oven heating wall comprising 50 courses of blocks, each block having two conjoint recesses in two of its adjoining faces, and having a connecting section in the corner away from said recesses, the blocks of each course being laid with their connecting sections all facing in the same direction along the length of the wall but with their connecting sections alternately at the top and at the bottom of the course, and the connecting sections of successive courses 55 facing alternately toward the opposite ends of the wall, substantially as described.

3. A coke oven heating wall comprising 60 courses of blocks, each block having two conjoint recesses in two of its adjoining faces, and having a connecting section in the corner away from said recesses, the blocks in the successive courses being laid to bring their connecting sections together, and the connecting sections of the blocks 65 comprising more than fifty per cent. of the total height of their respective courses, whereby gases traveling lengthwise of the wall are compelled to pass alternately up and down as they pass said connecting sections, substantially as described.

4. A coke oven heating wall comprising 70 courses of blocks, each block having a connecting section in one of its corners, its remaining corners and the faces intermediate 75 said remaining corners being recessed, the blocks being laid in the courses with the connecting sections of blocks of adjacent courses together, and the connecting sections comprising more than fifty per cent. of the 80 height of the wall, whereby gases traveling lengthwise of the wall are compelled to pass alternately up and down as they pass the connecting sections, substantially as described.

ARTHUR ROBERTS.
